The Cornelius Company, Anoka, Minn.

Filed June 23, 1970, Ser. No. 23,633

Term of patent 14 years

Int. Cl. D15—08

U.S. Cl. D94—3

FIG. 1 is a front elevational view of a double flavor drink dispensing valve unit showing my new design.

FIG. 2 is a top view thereof.

FIG. 3 is a side view thereof, the opposite side having a similar but reversed appearance.

The dominant features of my design reside in that portion of the article shown at the side of the line A—A indicated by the arrows.

I claim:

The ornamental design for a double flavor drink dispensing valve unit or similar article, substantially as shown and described.
